UNITED STATES PATENT OFFICE

KARL RICHARD LIEBERKNECHT, OF OBERLUNGWITZ, GERMANY, ASSIGNOR TO KARL LIEBERKNECHT G. M. B. H., OF OBERLUNGWITZ, GERMANY, A CORPORATION OF GERMANY

NEEDLE BAR FOR STRAIGHT KNITTING MACHINES

Application filed October 28, 1931, Serial No. 571,657, and in Germany October 28, 1930.

This invention relates to the needle bar of a straight knitting machine and more particularly to a straight knitting machine adapted to produce a complete stocking on the one machine by the employment of a needle bar having a pivoted section which can be swung out of the row of needles. While in making any one stocking it is preferable to keep the width of the swinging portion of the needle bar of this type of machine of an unchanged width, it is desirable to have this swinging portion adjustable in order that the machine may knit different sizes of stockings. For a process for making both the leg and foot of a stocking on one machine, reference is made to my copending application Serial No. 558,811, filed August 22, 1931, and German Pat. No. 543,597 of Feb. 8, 1932, corresponding thereto.

According to the present invention it is possible to make stockings of various sizes in their entirety on the one machine by having the pivoted portion of the needle bar of a variable width. To this end separate additional needle carriers of one or more needles each are inserted between the pivoted section of the needle bar and the fixed main portion of that bar, and these separate carriers can be coupled up at will with either the main swinging section or the fixed portion of the needle bar. It is an advantage to have these needle carriers themselves removable and arranged so that they revolve on the same axis as that of the pivoted portion of the needle bar. These additional needle carriers are made as thin as possible so that there may be a great variety of width of work available. The additional carriers are made readily detachable to facilitate easy and rapid replacement if the needles become damaged. All these advantages are obtained by making these separate carriers in the form of pivoted shapes which are merely hooked on to the shaft. It will be understood of course that various shapes of carriers and various manners of attachment are possible.

In the drawing,

Figure 1 is a front view of a needle bar made according to the present invention;

Figure 2 is a vertical section through the

needle bar at right angles to the bar, taken on the line 1—1 of Figure 2 in the direction of the small arrows;

Figure 3 is a side view of one of the additional needle carriers;

Figure 4 is an edge view of an additional needle carrier; while

Figure 5 is a plan view of the needle bar shown in Figure 1.

Referring now to the drawing, the usual rear bed 2 is mounted on the machine frame 1 with the sinker head 3, the sinkers 4 and the verge plate 5 carried thereon in the usual manner. The knocking-over comb 6 is fastened to a frame 7 which in turn is united to a lever 8. This lever 8 is on the knocking-over shaft 9 and is moved by it so that the knocking-over comb 6 receives the usual vertical motion at the proper time.

In front of the knocking-over comb 6 is located the needle bar which comprises two relatively fixed side portions 10 and 11 and a center portion 12 which can be swung out of line. In order that the width of the pivoted middle portion 12 may be altered at will, needle carriers 13 are introduced between the fixed or main portions 10 and 11 and the pivoted middle portion 12.

The two fixed portions 10 and 11 are connected on their rear faces by a rail 14. Formed on these fixed side portions 10 and 11 are small eyes or lugs 15, 16. Fastened to the front of the pivoted middle portion 12 is a similar horizontal rail 17 extending laterally beyond the sides of the pivoted middle portion and overlapping but below the eyes 15, 16. This rail 17 therefore lies in front of all the additional pivoted needle carriers 13 as well as the pivoted middle portion 12. When the pivoted middle portion 12 with its rail 17 is swung outwardly to idle position, as shown for instance in Figure 2, the separate additional needle carriers 13 also tend to be pulled out owing to the tension of the fabric on them and to come to rest against this front rail 17. However if the size of stocking which is being knit does not call for the maximum number of additional individual needle carriers being made idle along with the pivoted center portion 12 of the

needle bar, some of the individual needle carriers 13 can be held in line with the main side portions 10 and 11 of the needle bar by means of bolts 18, 19 which move longitudinally of the needle bar through the eyes or lugs 15, 16 in the side portions 10 and 11. Such individual needle carriers 13 as are held by these bolts 18, 19 are held against the back rail 14 and prevented from swinging out. If it is desired to increase the width of the pivoted needle portion the bolts 18, 19 are moved laterally further outward so that a greater number of the individual pivoted needle carriers 13 swing free of the bolts and can move out to the position permitted by the front rail 17. If a narrower middle portion is desired the bolts are pushed further inward so that a greater number of individual needle carriers are clamped between the back rail 14 and the bolts 18, 19. The maximum width of pivoted center portion attainable is when the bolts 18 and 19 are pushed completely apart and all the pivoted individual needle carriers are free to swing with the center portion 12. The minimum width is attained when the bolts 18 and 19 cover all the individual pivoted needle carriers and only the middle portion 12 of the needle bar is able to swing outwardly.

As already mentioned, the number of individual pivoted needle carriers 13 inserted between the fixed portions 10 and 11 and the pivoted middle portion 12 is entirely a matter of choice, being variable from one individual pivoted needle carrier on each side of the middle portion 12 to a construction in which the side pieces 10 and 11 are almost entirely replaced by the individual pivoted needle carriers.

As already mentioned, the individual pivoted needle carriers 13 may be of any desired shape though it is advantageous to use the pendulum-like form shown in Figures 3 and 4 of the drawings, because this form is one which is easy to replace. The needles 20 may be soldered into the needle carriers 13 or cast or clamped in or fastened in any other desired manner and the number of needles in each individual pivoted needle carrier is also arbitrary, it being possible to put one or more in each carrier.

During knitting of the leg the pivoted middle portion 12 of the needle bar is held in alignment with the two fixed portions 10 and 11 by means of latch detent springs 25 fastened on lugs 23 which in turn are integral with the fixed portions 10 and 11 of the needle bar. These latch detent springs 25 engage recesses 27 at the ends of rail 17 of the pivoted middle section 12. When the instep portion of the stocking is reached the needle bar is swung out of line, the entire row of needles being in line at all other times. The detent springs 25 are then released from the recesses 27 for this purpose and the

pivoted bar is swung outward until the detent springs engage recesses 28. This is during the making of the heel tabs. In this way the middle portion 12 and the individual pivoted needle carriers 13 which are not clamped between the rail 14 and the bolts 18 and 19 are swung out of position and held as described in my copending application serial No. 558, 811 and German Pat. No. 543,597 of Feb. 8, 1932, corresponding thereto. With the detent springs engaging recesses 28 the heel tabs are partly knit the fabric is then knocked off from the needles, assuming a folded position between the sinkers and knocking over tabs. After twenty or twenty five courses are knit in this manner, the detent springs 25 are entirely disengaged from the rail 17 so that the pivoted section under the influence of the tension of the fabric is gradually swung outwardly as the heel tabs increase in length. When the heel tabs are of the desired length, they are pressed off and the pivoted middle section 12 and the individual pivoted needle carriers 13 are pushed back into alignment with the fixed portions 10 and 11 of the needle bar. The lever 21 serves to produce the vertical motion of the needle bar and the fork 22 controls the horizontal motion as usual.

Modifications which do not depart from the scope of my invention will be obvious to those skilled in the art.

What I claim is:

1. In a straight knitting machine having a needle bar, a pivoted needle bar portion and a fixed needle bar portion, in combination with one or more separate additional needle carriers located between said pivoted and fixed needle bar portions.

2. In a straight knitting machine having a needle bar, a pivoted needle bar portion, a fixed needle bar portion and one or more additional needle carriers pivotally mounted between said parts and adapted to act as part of either portion, in combination with means adapted to couple said additional carriers to said fixed portion.

3. In a straight knitting machine having a needle bar, a pivoted needle bar portion, a fixed needle bar portion and a plurality of additional needle carriers pivotally mounted between said portions, in combination with means on said fixed portion adapted to couple to said fixed bar portion a variable number of said additional carriers.

4. In a straight knitting machine having a needle bar, a pivoted needle bar portion, a fixed needle bar portion and a plurality of additional needle carriers pivoted between said pivoted and fixed portions on the same axis as, and adapted to act as part of, said pivoted portion; in combination with locking means on said fixed portion adapted to leave said additional carriers free to act as part of said pivoted portion or to couple one or more

of said additional carriers to said fixed portion.

5. In a straight knitting machine having a pivoted needle bar portion, a fixed needle bar portion and a plurality of additional needle carriers between said pivoted and fixed portions pivoting about the same axis as the pivoted portion and adapted to act as part of either portion, said additional needle carriers being detachable from the axis on which they are mounted.

10 6. In a straight knitting machine having a needle bar, a pivoted needle bar portion, a fixed needle bar portion, and a plurality of additional needle carriers pivotally mounted between said portions, in combination with means on said pivoted portion to hold additional carriers in swung out position and means on said fixed portion capable of coupling additional carriers to said fixed portion.

15 In testimony whereof I have signed my name to this specification.

KARL RICHARD LIEBERKNECHT.

of said additional carriers to said fixed portion.

5. In a straight knitting machine having a pivoted needle bar portion, a fixed needle bar portion and a plurality of additional needle carriers between said pivoted and fixed portions pivoting about the same axis as the pivoted portion and adapted to act as part of either portion, said additional needle carriers being detachable from the axis on which they are mounted.

10 6. In a straight knitting machine having a needle bar, a pivoted needle bar portion, a fixed needle bar portion, and a plurality of additional needle carriers pivotally mounted between said portions, in combination with means on said pivoted portion to hold additional carriers in swung out position and means on said fixed portion capable of coupling additional carriers to said fixed portion.

15 In testimony whereof I have signed my name to this specification.
